UNITED STATES PATENT OFFICE.

PAUL HANSON, OF WILD HORSE, COLORADO.

AUTOMATIC COUNTER AND STOP DEVICE.

1,147,798.

Specification of Letters Patent. Patented July 27, 1915.

Application filed January 12, 1912. Serial No. 670,744.

To all whom it may concern:

Be it known that I, PAUL HANSON, a citizen of the United States, residing at Wild Horse, in the county of Cheyenne and State 5 of Colorado, have invented a new and useful Improvement in Automatic Counter and Stop Devices, of which the following is a specification.

My invention relates to improvements in 10 counters for use in connection with a revolute or reciprocable member whereby at the end of a predetermined number of movements of said member, a driving member is adapted to be disconnected from said movable member and to automatically disconnect the latter.

The primary object in my invention is 20 the production of a simple, inexpensive and effective device which will not get out of working order under rough usage and which can be easily attached to machinery.

In the accompanying drawings forming part of this specification, Figure 1 is a side elevation of my invention, a detail of the 25 revolute member being shown and a shifting lever for a clutch illustrated in section; Fig. 2 is a plan of the construction illustrated in Fig. 1, a detail of the revolute element not being shown; Fig. 3 is a side 30 elevation of my invention showing the pitman in superior position and the dog supported out of engagement with the ratchet wheel when the counter is out of operation; Fig. 4 is a plan of the construction illustrated in Fig. 3, the pitman being shown 35 in section and its spring removed; Fig. 5 is a sectional view of a detail illustrating the construction employed in mounting the ratchet wheel and head frame of my invention; Fig. 6 is a side elevation of a churn 40 showing my invention applied thereto for use; Fig. 7 is an end view of the construction illustrated in Fig. 6; Fig. 8 is a side elevation of an alternative construction of 45 my invention; Fig. 9 is a plan of the construction illustrated in Fig. 8 and Fig. 10 is an end view of the construction illustrated in Fig. 8, the rack bar being shown in section and the trip lever, dog and actuating 50 spring removed.

For convenience in describing my invention and its application in use, I have shown the same applied to a churn as illustrated in Figs. 6 and 7 but it is to be understood that 55 the invention may be used with any device

wherein it is desirable to disconnect the driven element from the driving element after a predetermined number of revolutions of the revolute member.

In the drawings A represents a revolute 60 receptacle suitably journaled at 2 in the main supporting frame B, said receptacle being adapted to be revolved by the driving shaft 3 which carries the driving member 4 of a friction clutch. 5 represents the 65 driven member of said clutch which is carried by a sleeve 6 journaled on the shaft 3, said sleeve in turn carrying a driving pinion 7, the teeth of which mesh with the teeth of the main gear 8 mounted on the 70 receptacle A. It is to be understood that it is immaterial how this driving mechanism is constructed, it forming no novel feature of my invention. The clutch too may be replaced by tight and loose belt pulleys. 75

C represents my improved counter which is mounted upon the frame B and adapted to operate the lever 9 to slide the driven member 5 of the clutch into and out of operative connection with the driving member 80 4. The lever mentioned is pivoted between its ends by bolt 10 (see Fig. 7) passing through said lever and a bracket 11, said bracket being secured on the frame B. The work end of said lever is bifurcated, its 85 arms forming a yoke 12 spanning the sleeve 6 and pivotally connected thereto by studs 13 (see Fig. 6) carried by the arms of the yoke and projecting freely into a circumferential slot 14 in the sleeve 6, this 90 construction being obviously ordinary for the purpose of causing the clutch to operate in the usual manner.

My improved counter consists of a ratchet wheel 15 the teeth 16 of which are 95 adapted to be engaged by the dog 17 and the wheel moved forward, a tooth at a time each revolution of the receptacle A. The ratchet wheel 15 is freely journaled upon a collar 18, (see Fig. 5) said collar in turn 100 being mounted upon a bolt 19 which is secured in an arm 20 of the bracket 11. A head frame D is also supported by the bolt 19, said frame being flanged at 21 to form a channel in which the arm 20 is seated, 105 said bolt 19 passing through the head frame and the arm 20 to clamp the parts together and rigidly support the head frame above the ratchet wheel.

Above the lower end of the head frame 110

which is secured to the bracket 11, a rocker arm 22 is pivoted between its ends upon a bolt 23 which is secured in the head frame. The upper end of this rocker arm is positioned in the path of the tripping shoulder 24 which is carried upon the end of the receptacle A so that during each revolution of the receptacle the rocker arm is caused to be tripped by the shoulder 24 sweeping over 5 the free end 25 of said arm. The lower end of the rocker arm is pivotally attached by means of a bolt 26 to the dog 17. The shoulder 27 of said dog engages a tooth on the ratchet wheel and draws the ratchet wheel 10 forward a step at a time each revolution of the receptacle. The shoulder 27 is beveled back at 28 so as to sweep over the teeth during backward movement of the dog and the dog 17 is held down against the teeth by a 15 spring 29. The free end of the rocker arm 22 is pressed forward to hold the same in the path of the trip shoulder 24 by means of an expansion spring 30 interposed between the end 25 of the rocker arm and the shoulder 20 31 formed on the head frame, points 32 being formed on the arm 25 and the shoulder 31 around which the ends of the spring 30 are seated and held. Forward movement of the arm 25 is limited normally by the 25 lower end of rocker arm 22 impinging against a stop shoulder 33 on the head frame. Backward movement of the ratchet wheel 15 is prevented by means of a pin 34 playing vertically in lugs 35 on the head 30 frame and dropping by gravity back of a tooth while the ratchet wheel is stationary or moving forward a step. A split key 36 passing through the pin 34 between and spaced from the lugs 35 prevents the normal 35 removal of the pin from its support. Forward movement of the ratchet wheel raises the pin over the teeth until it drops by gravity back of a tooth to prevent backward motion.

40 When it is desired to throw the counter out of operation the end 25 of the rocker arm may be moved back by hand and the dog 17 raised into the receptacle 37 which is formed by a curved flange on the side of the head frame. The position which the parts assume being illustrated in Fig. 3 of the drawings. In this manner the rocker arm is held out of the path of the tripping shoulder 24 and the dog is supported out of 45 engagement with the teeth 16 on the ratchet wheel.

45 The free end 40 of the shifting lever 9 is positioned in the path of a pitman rod 41 which extends diametrically from the ratchet wheel 15, said pitman rod being connected to the wheel by a pivot stud 42 and a split key 43. The free end of the pitman rod rests normally upon the free end 40 of the shifting lever 9 and otherwise engages 50 the shifting lever by means of collars 44 and 55

45 to swing the lever and throw the clutch into and out of operation. The collar or follower 45 slides freely upon the pitman rod, an actuating spring 46 being interposed on said rod between the collar 45 and a back stop in the form of a washer 47 which is held upon said rod by the pin 48 passing through one of the openings 49 in said rod. During the revolution of the churn after the ratchet wheel has been set for a predetermined number of revolutions according to the scale of numerals 50 marked opposite the teeth on said wheel, starting from zero, the ratchet wheel is moved forward, step by step each time the receptacle revolves carrying with it the pitman rod 41 and compressing the spring 46 while the collar 45 impinges against the shifting rod 40 until the desired number of revolutions have been made whereupon the pitman rod passes its 60 dead center illustrated in Fig. 1, the spring 46 and the momentum of wheel 15 then causing the block 44 to engage the shifting rod 40 and release the clutch out of engagement, thus stopping the receptacle.

65 Stationary collar 44 is formed with a lug 51 on its side which engages back of the shoulder 27 on the dog 17 when the pitman rod 40 is raised into vertical or superior position as illustrated in Fig. 3, and assists in 70 holding the pitman rod. The stop 52 formed on the head frame in the path of the pitman rod prevents said rod from moving in the other direction. The collars 44 and 45 are formed with downwardly converging shoulders 53 and 54 which serve to guide the pitman rod into engagement with the end 40 of the arm 9 and prevent disengagement of said parts when the device is in 75 operation.

80 In use, for illustration, if it is desired that the receptacle shall revolve 10 revolutions and then stop, the ratchet wheel is turned by hand in the direction of the arrow illustrated in Fig. 1 until tooth No. 10 (which in that event would be the starting point) is opposite the shoulder 27 of the dog 17 whereupon revolution of the receptacle causes the pitman rod upon passing dead center after the receptacle has revolved ten times to move ahead through the action of the spring 46 and to disengage the clutch, thus stopping the receptacle. When numbering the teeth on the wheel the numbers are placed so that after allowance has been 85 made for the clutch being released one point or tooth after dead center has been passed the zero tooth will be engaged by the dog 17. As shown in Fig. 1 the device is set to release the pitman rod 41 to effect the stopping of the churn after one revolution of the churn. The adjusting of the tension of the spring by selectively placing the stop 47 by inserting the fastening key 48 through 90 one of the openings 49 in the rod 41 en-

95 100 105 110 115 120 125 130

ables the setting of the device so that it can be made to trip after one point or tooth has passed dead center. Should for any reason the strength of the restraining spring 46 5 not be sufficient to cause the release of the clutch immediately after the pitman passes a tooth or point following dead center, further revolution of the receptacle causes the ratchet wheel 15 to be positively driven forward away from dead center, thus moving the shifting rod 40 by collar 44 and positively releasing the clutch. While the pitman rod is moving toward dead center the constantly increasing compression of spring 15 10 holds the lever 9 and clutch set under increasing pressure until the dead center point of the pitman rod is passed. The releasing of the clutch is directly produced by the collar 44 impinging against lever 9. The further revolution of the ratchet wheel after the spring 46 has partially relaxed causes the clutch to be further positively separated out of connection by the collar 44 impinging 20 against lever 40, the tension of spring 46 25 remaining substantially constant during this period. The openings 49 through the pitman rod 41 are longitudinally spaced apart to permit the stop 47 to be adjusted on said rod in operative position, said openings being 30 adapted to receive the fastening key 48 of said collar. By moving the stop up a step the restraining spring 46 is compressed and the strength developed for moving the shifting lever 9 made greater and more 35 positive.

My invention is not confined to use with the revoluble member shown which it is desired to stop at a predetermined number of revolutions it being applicable for stopping 40 any movable member after a predetermined number of movements thereof. My invention may be used when desired without the restraining spring 46 and its engaging members for shifting the lever 9, the stop 44 45 being allowed to drag over and into engagement with the lever 40 during the forward movement of the ratchet wheel and by the continued movement of the ratchet wheel force the lever 40 forward positively thus 50 shifting the clutch out of operation after a predetermined number of movements.

In Figs. 8 to 10 inclusive I have illustrated an alternative construction of my invention in which the dog 60 is reciprocated 55 by means of a trip arm 61 and caused to engage and move the rack bar 62 forward by said dog engaging a tooth each time the trip shoulder 61 is reciprocated by the movable member. The rack bar receives the shifting 60 lever 63 in a slot having free play therein until the movable member has made a predetermined number of movements whereupon the rack bar having been set accordingly, is adapted to push the lever and positively shift the clutch out of operation with

which the lever is connected by the end of said slot impinging against the edge of the lever. Normally the dog 60 plays freely in the guide 64 in the rigid frame 65 but when it is desired to set the counter so that it will not operate the dog is lifted and placed with the shoulder 66 over the pin 67 on said frame in which position it is held out of engagement with the rack and with the trip shoulder 61, restrained out of the path of the movable member. The rack 62 slides in a gibway 68 but is retarded in its movements by the spring 69 pressing through the gibway against the lower surface of the rack. The spring 69 prevents the rack bar from slipping back while the dog 60 is engaging the succeeding tooth. The rack bar is adapted to be adjusted according to its scale 70 by engaging the lug 71 on its side, a spring 72 is employed tending to depress the dog 75 into engagement with a tooth of the rack bar and also return the trip lever 61 in the path of the shoulder 73 on the movable member 74 after each tripping operation of the device. The set bolt 75 is also employed 80 to regulate the throw of the trip lever 61 and the dog 60 which it carries.

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. The combination with a revoluble driven element, of a driving element, a clutch interposed between said driving and driven elements, shifting means for throwing said clutch into and out of operation, a ratchet wheel, means pivotally connected with said ratchet wheel for reciprocating said shifting means, pivoted means adapted to move said ratchet wheel, and a shoulder carried by said driven element to intermittently engage said pivoted means to cause a step-by-step movement of said ratchet wheel.

2. The combination with a revoluble driven element, of a driving element, a clutch interposed between said driving and driven elements, shifting means for throwing said clutch into and out of operation, a ratchet wheel, means pivotally connected with said ratchet wheel for reciprocating said shifting means, pivoted means adapted to move said ratchet wheel in one direction, a gravity pin for preventing reverse movement of said ratchet wheel, and a shoulder carried by said driven element to intermitt-

tently engage said pivoted means to cause a step-by-step movement of said ratchet wheel.

3. Apparatus of the class set forth, comprising, in combination, a supporting frame, a revoluble driven element journaled on said frame, a driving element, means for throwing said driven element out of connection with said driving element, said means having a shifting arm, a counter mounted on said frame having a ratchet wheel and stepping mechanism for said ratchet wheel adapted to be operated during the revolution of said revoluble element, a pitman rod journaled upon and adapted to be reciprocated by said wheel and extending toward said arm and a restraining element carried by said rod and adapted to engage and hold said arm under pressure during the stepping forward of said ratchet wheel a predetermined number of steps and to relax from said arm upon the completion of said steps and immediately after the journal point between said wheel and rod passes beyond dead center.

4. Apparatus of the class set forth comprising in combination, a supporting frame, a revoluble driven element journaled on said frame, a driving element, means for throwing said driven and driving elements into and out of operation, said means having a shifting arm, a counter mounted on said frame having a ratchet wheel and stepping mechanism for said ratchet wheel adapted to be operated to move said wheel forward a step at a time each revolution of said revoluble element, a pitman rod journaled upon and adapted to be reciprocated each time said wheel revolves, said rod extending toward said arm, a restraining element carried by said rod and adapted to engage and hold one side of said arm under spring pressure while said ratchet wheel advances toward dead center a predetermined number of steps and to relax from said arm immediately after the journal point of said rod passes over dead center, and a stop carried by said rod to engage said arm on the opposite side from said restraining element and adapted to positively move said arm after said journal point is moved past said dead center.

5. Apparatus of the class set forth comprising in combination, a supporting frame, a revoluble driven element journaled on said frame, a driving element, a lever for throwing said driving and driven elements into and out of operation, said frame having a ratchet wheel and stepping mechanism for said ratchet wheel adapted to be operated to move said wheel forward a step at a time each revolution of said revoluble element, a pitman rod journaled upon and adapted to be reciprocated each time said wheel revolves, said rod extending toward said le-

ver, a restraining element carried by said rod on one side of said lever and a stop carried by said rod on the other side of said lever, said restraining element and stop having downwardly converging shoulders adapted to freely embrace said lever to swing the same, said restraining element engaging one side of said lever under pressure while said ratchet wheel is being stepped forward toward dead center a predetermined number of times and serving to assist in releasing said lever immediately after the journal point of said rod passes dead center and said stop being adapted to positively move said lever after said journal point passes dead center.

6. A device of the type described comprising counter adapted to coöperate with a shifting lever for causing a driven element to coöperate with a driving element, comprising in combination, a supporting frame, a head frame mounted thereon, a ratchet wheel journaled on said head frame, a dog adapted to engage the teeth of said wheel to step the latter forwardly, a rocker arm journaled on said head frame, one end thereof being adapted to freely support said dog and its other end acting as a trip arm, a spring acting against said rocker arm to return said dog into reengagement with the teeth of said wheel, a stop engaging said teeth to prevent reverse movement of said wheel, a pitman rod journaled on a side of said wheel to be reciprocated thereby each revolution thereof, and restraining means on said rod adapted to engage said lever and to be compressed while said wheel is stepped a predetermined number of times and relaxed upon the completion of said steps and upon the journal point of said wheel and pitman rod passing over dead center.

7. The combination with a revoluble driven element, of a driving element, a clutch interposed between said driving and driven elements, an arm pivoted intermediate its ends, said arm being secured at one end to said clutch, a ratchet wheel, a pitman rod connected at one end to said ratchet wheel and operatively engaging the free end of said arm to alternately connect and disconnect said driving and driven elements, pivoted means adapted to move said ratchet wheel in one direction, a gravity pin for preventing reverse movement of said ratchet wheel, and a shoulder carried by said driven element to intermittently engage said pivoted means to cause a step-by-step movement of said ratchet wheel.

8. A device of the type described comprising counter having a ratchet wheel, and ratchet mechanism for stepping said wheel forwardly, a support, a head frame carried by said support and on which said wheel is journaled and said ratchet mechanism mounted, a pitman rod journaled on the face

- of said wheel at a point eccentric to the axis thereof and adapted to be reciprocated, a clutch shifting lever, means for detachably securing said pitman rod to said lever, said rod being adapted to be turned into upright position on its journal when not in use, said detachable means having a lug in the path of said ratchet mechanism and said head frame having a back stop formed thereon in the path of said rod, whereby said rod is adapted to be held in raised position between said stop and part of said stepping mechanism.
9. A device of the type described comprising counter having a ratchet wheel, and ratchet mechanism for stepping said wheel forwardly, said ratchet mechanism having a rocker arm and a dog pivotally supported by the lower end of said rocker arm, its free end being adapted to engage the teeth of said ratchet wheel to step said wheel forwardly, said dog having a shoulder adjacent its teeth engaging end, a head frame on which said wheel and rocker arm are journaled and formed with a forwardly projecting shoulder and flange, said flange forming a receptacle to receive and hold the free end of said dog when the latter is raised out of engagement with the teeth of said wheel, a pitman rod journaled on the face of said wheel and adapted to be reciprocated each revolution of the wheel, a clutch shifting element and a restraining element and stop carried by said rod and adapted to engage said clutch shifting element, said stop being formed with a lug and said pitman rod when not in use being adapted to be raised into upright position against the stop on said head frame and with said lug engaging back of the shoulder on said dog.
10. A device of the type described comprising counter having a ratchet wheel, and ratchet mechanism for stepping said wheel forwardly, a head frame on which said wheel is journaled and said ratchet mechanism is mounted, said ratchet mechanism having a dog and said ratchet wheel a scale indicating the number of teeth thereon, a clutch shifting element, a pitman rod journaled on one of the faces of said wheel eccentric to the axis of the latter, restraining means carried by said rod and adapted to be compressed by engagement with the clutch shifting element during the forward movement of said wheel and adapted to assist in releasing said clutch shifting element after the journal between said wheel and rod passes over dead center, for the purpose specified.
11. A device of the type described comprising counter having a ratchet wheel and ratchet mechanism for stepping said wheel forwardly, a head frame on which said wheel is journaled and said ratchet mechanism mounted, a clutch shifting lever, a pitman rod journaled on and adapted to be reciprocated each revolution of said wheel, a restraining element mounted upon said rod and adapted to assist in releasing said lever after the journal of said rod passes over dead center, a second engagement longitudinally adjustable on said rod and adapted to positively engage said lever after said restraining element has passed over dead center and relaxed its energy and a pin passing into said rod to hold said restraining element in place, said rod having a series of openings to receive said pin, and said series being disposed longitudinally of the rod whereby said pin may be engaged with the rod to selectively position said restraining element on the rod.
12. The combination with a revoluble driven element, of a driving element, a clutch interposed between said driving and driven elements, a pivoted arm secured at one end to said clutch, a ratchet wheel, a pitman rod connected at one end to said ratchet wheel, a follower carried by said pitman rod adapted to engage the free end of said pivoted arm, for throwing said clutch into engagement, a stop carried by said pitman rod for throwing said clutch out of engagement, pivoted means adapted to rotate said ratchet wheel, and means carried by said driven member to intermittently contact with said pivoted means for causing a step-by-step movement of said ratchet wheel.
13. The combination with a revoluble driven element, of a driving element, a clutch interposed between said driving and driven elements, an arm pivoted intermediate its ends, one end of said arm being secured to said clutch, a ratchet wheel, a pitman rod connected at one end to said ratchet wheel, a spring-pressed follower carried by said pitman rod engaging the free end of said pivoted arm for throwing said clutch into engagement, an adjustable stop carried by said pitman rod for throwing said clutch out of engagement, pivoted means adapted to rotate said ratchet wheel, and means carried by said driven member to intermittently contact with said pivoted means for causing a step-by-step movement of said ratchet wheel.
14. The combination with a revoluble driven element, of a driving element, a clutch interposed between said driving and driven elements, shifting means for throwing said clutch into and out of engagement, a head frame, a ratchet wheel rotatably mounted in said frame, a pitman rod connected to said ratchet wheel and operatively engaging said shifting means, an arm pivoted intermediate its ends to said frame, a dog carried by said arm and engaging said ratchet wheel to move it in one direction, compression means co-acting with said arm

to normally retain said dog in engagement with said ratchet wheel, and a projection on said driven member intermittently contacting with said arm to cause a step-by-step movement of said ratchet wheel.

- 5 15. The combination with a revolute driven element, a driving element, a clutch interposed between said driving and driven elements, shifting means for throwing said 10 clutch into and out of operation, a ratchet member, having a connection with said shifting means to reciprocate the same, pivoted means adapted to move said ratchet member, and a shoulder carried by said driven element to intermittently engage said pivoted means to cause a step-by-step movement of 15 said ratchet member.
16. The combination with a revolute

driven element having a detachable driving element, of shifting means for connecting 20 and disconnecting said driving and driven elements, a ratchet member having an operating connection with said shifting means, pivoted means adapted to move said ratchet member, and a shoulder carried by said 25 driven element adapted to engage said pivoted means to cause the movement of said ratchet member.

In testimony whereof, I have signed my name to this specification, in the presence of 30 two subscribing witnesses.

PAUL HANSON.
